FIG. 3.

FIG. 1.

FIG. 2.

P. J. Ryan, Inventor.

By his attorney Thomas Keitch.

UNITED STATES PATENT OFFICE.

PATRICK J. RYAN, OF BROOKLYN, NEW YORK, ASSIGNOR OF ONE-HALF TO RICHARD DOUGHTY, OF NEW YORK, N. Y.

ANCHOR.

1,289,551.

Specification of Letters Patent. Patented Dec. 31, 1918.

Application filed October 12, 1917. Serial No. 196,150.

To all whom it may concern:

Be it known that I, PATRICK J. RYAN, a citizen of the United States, and a resident of 2142 80th street, Brooklyn, in the county of Queens and State of New York, have invented certain new and useful Improvements in Anchors, of which the following is a specification.

My invention relates to an improvement 10 in anchors for vessels but particularly to anchors of the stockless type and has for its object the provision of a means for causing the anchor flukes to quickly and positively embed themselves in the mud or sand at the sea bottom when the anchor is brought into use.

The old form of anchor which comprised a stock and flukes integrally forged therewith has been almost entirely superceded by the stockless type. This latter type has a 20 shank to which the crown is pivoted in such a way that the flukes, carried by the crown, may swing to either side of the shank approximately 45 degrees for engaging with the sea bottom. The swinging of the flukes, 25 when the anchor is brought into use, is accomplished by a widening of the crown at the rear which drags in the sand or mud on the sea bottom and causes the flukes to swing downwardly into position. It is obvious 30 that this action is not a positive one and that the flukes do not always engage quickly; therefore I have provided in my invention a tripping device pivoted to the crown that engages as soon as the anchor is 35 grounded and which, through this engagement immediately forces the flukes into the bottom when the first strain comes on the cable.

The objects of my invention as set forth 40 above and others that will later appear together with the particular methods of attaining these are now to be described and are illustrated in the accompanying drawings forming part of this specification.

Similar characters of reference denote like 45 or corresponding parts throughout the several views; of which Figure 1 is a side elevation of my invention, partly in section A, B, C, D; Fig. 2 is a vertical cross section on lines E, F, G, H of Fig. 1; Fig. 3 is a perspective view of the tripping device of my anchor.

Referring particularly to Figs. 1 and 2 of the drawings, numeral 1 represents the 50 anchor crown to which the flukes 2 and 3 are

attached preferably by an integral casting. The crown 1 has a rectangular pocket 4 cored from the rear and this intersects with a slot 5 in the front. At the bottom of the pocket 4 and on either side of the slot 5 are two 60 semi-cylindrical grooves 6 and 7 which serve as bearing sockets for the gudgeon pin-like projections 8 and 9 of the shank 10. This shank is entered into place, from the rear, before the shackle 11 and the pin 12 are assembled. The extreme inner end of the shank is formed into two gear shaped teeth 13 and 14, extending each, one half the width of the shank end and staggered so as to engage and co-act with two similar teeth 15 70 and 16 formed on the fluke tripping device 17, which is pivoted by the pin 18 between the crown lugs 19 and 20. Fig. 3 shows a separate view of the tripping device and here is clearly illustrated the manner of staggering the teeth and also the forwardly curved flukes 21 and 22, either of which immediately engages the sea bottom when the anchor is first grounded and when the cable 75 draws the anchor in the direction of the arrow (see Fig. 2) the engaged fluke of the tripping device causes either tooth 15 or 16 to bear against tooth 14 or 13 of the shank 80 and thus throws anchor flukes 2 and 3 into the bottom.

The tripping device 17 has another function, that of holding the shank up in its place. It thus performs the additional important duty of tripping the flukes into position without increasing the number of 90 parts over that required in other stockless anchors.

My invention readily conforms to the United States and other Government specifications and can be built as cheaply as any 95 stockless anchor now being used. Another important feature of my invention is that by causing the anchor flukes to engage promptly all danger of the anchor rolling is avoided and this feature alone is of the 100 utmost importance.

Having thus fully described my invention so that anyone skilled in the art may make and construct the same and without limiting myself to any of the details of construction 105 or arrangement of parts, I claim:

1. In an anchor comprising a crown and flukes, a shank journaled therein, and means pivoted in the crown and co-acting with the shank for moving the flukes. 110

2. In an anchor comprising a crown and flukes, a shank journaled therein, and bottom engaging means pivoted in the crown and co-acting with the shank for moving the flukes. 55
3. In an anchor comprising a crown and flukes, a shank journaled therein, and means pivoted in the crown and co-acting with the shank for effecting a relative movement between the shank and flukes. 10
4. In an anchor comprising a crown and flukes, a shank journaled therein, and bottom engaging means pivoted in the crown and co-acting with the shank for effecting a relative movement between the shank and flukes. 15
5. In a stockless anchor, means connected to the crown for holding the shank in place and for effecting an angular movement of the shank relative to the crown. 20
6. In a stockless anchor, bottom engaging means connected to the crown for holding the shank in place and for effecting an angular movement of the shank relative to the crown. 25
7. In a stockless anchor, means capable of oscillation connected to the crown for holding the shank in place and for effecting an angular movement of the shank relative to the crown. 30
8. In an anchor comprising a crown and flukes, a shank journaled therein, and means pivoted in the crown and co-acting with the shank through staggered teeth formed on each, for moving the flukes. 35
9. In an anchor comprising a crown and flukes, a shank journaled therein, and means pivoted in the crown and co-acting with the shank through staggered teeth formed on each, for moving the flukes in either direction. 40
10. In an anchor comprising a crown and flukes, a shank journaled therein, and means pivoted in the crown and co-acting with the shank for moving the flukes in either direction. 45
11. In a stockless anchor, means connected to and movable relative to the crown and co-acting with the shank for effecting an engagement of the flukes when the anchor is drawn forward on the bottom. 50
12. In a stockless anchor, crescent shaped means connected to and movable relative to the crown and co-acting with the shank for effecting an engagement of the flukes when the anchor is drawn forward on the bottom. 55
13. In a stockless anchor, means connected to and movable relative to the crown and co-acting with the shank, said means being adapted to engage the bottom and through said engagement to effect a setting of the anchor flukes. 60
14. In a stockless anchor, crescent shaped means connected to and movable relative to the crown and co-acting with the shank, said means being adapted to engage the bottom and through said engagement to effect a setting of the anchor flukes. 65
15. A stockless anchor comprising a fluked crown, a shank pivoted thereto, and a fluke-tripping device movably mounted upon said crown and adapted to cause relative movement between said shank and crown. 70
16. A stockless anchor comprising a fluked crown, a shank pivoted thereto, and a fluke-tripping device including means engaging said shank, said shank engaging means being wholly disposed within said crown. 75
17. A stockless anchor comprising a fluked crown, a shank pivoted thereto, and a fluke-tripping device movably mounted upon said crown in engagement with said shank for causing a relative movement between the latter and said crown. 80
18. A stockless anchor comprising a fluked crown, a shank pivoted thereto, and a fluke-tripping device movably mounted upon said crown in permanent engagement with said shank for causing a relative movement between the latter and said crown. 85
19. A stockless anchor comprising a fluked crown, a shank pivoted thereto, and a fluke-tripping device upon said crown in permanent engagement with said shank for causing a relative movement between said shank and said crown when the cable is strained. 90

Signed at New York city in the county of New York and State of New York, this 11th day of October, A. D. 1917.

P. J. RYAN.
